COVERED BOX OR CONTAINER

**Kenneth T. Buttery, Kalamazoo, Mich., assignor
to Sutherland Paper Company, Kalamazoo,
Mich.**

Application April 16, 1947, Serial No. 741,856

10 Claims. (Cl. 229—36)

1

This invention relates to improvements in a covered box or container.

The main objects of this invention are:

First, to provide a covered box or container which may be stored or shipped in the knockdown and quickly and easily set up for use and one in which the cover is effectively retained in closed position.

Second, to provide a box or container having these advantages in which the parts are so arranged as to provide a fairly rigid structure when erected even when formed of quite light box or container stock.

Third, to provide a box or container having these advantages which may be formed of an integral blank with substantially no waste in stock.

Further objects relating to details and economies of the invention will appear from the description to follow. The invention is defined and pointed out in the claims.

A structure which embodies the features of the invention is illustrated in the accompanying drawings, in which:

Fig. 1 is an end perspective view of a box or container embodying my invention, a portion of the cover being broken away to illustrate structural details and the relation of the cover to other parts.

Fig. 2 is a fragmentary perspective view partially in section on line 2—2 of Fig. 1 with the cover shown in closed position by full lines and in partially open position by dotted lines.

Fig. 3 is an inside perspective view of one corner of the box or container body.

Fig. 4 is a plan view of the structure collapsed.

Fig. 5 is a plan view of the blank from which the structure shown in Figs. 1 to 4 is formed.

Fig. 6 is a fragmentary perspective view of a modified form or embodiment of my invention, parts being broken away to show structural details.

Fig. 7 is a perspective view with the cover open.

Fig. 8 is an enlarged sectional view on line 8—8 of Fig. 7.

Fig. 9 is an enlarged fragmentary sectional view on line 9—9 of Fig. 6.

The embodiment of my invention illustrated in Figs. 1 to 5, inclusive, comprises a bottom 1, front and rear body walls 2 and 3 and body walls 4—4, a cover 5 which is hingedly connected to the upper edge of the rear body wall, and a cover front wall 6 which is hingedly connected to the swinging edge of the cover. Cover end walls 7—7 are hingedly connected to the ends of the cover. The front wall 2 is provided with front corner flaps 8—8 and the rear wall 3 is provided with rear corner flaps 9—9. The cover front wall 6 is provided with corner flaps 10—10. All of these parts are formed of an integral blank suitably scored and slit to provide hinging con-

2

nctions for the parts, the several scores being conventionally shown at 11. The body end walls are provided with the diagonally disposed weakening lines 12 which provided joint flaps 13—13 at the front ends of the body end walls. These joint flaps are collapsible on the outer sides of the body end walls and the corner flaps 8 of the front wall are secured thereto preferably adhesively.

The cover end walls have the diagonal weakening lines 14 providing triangular joint flaps 15 foldable on the outer sides of the cover end walls and to which the corner flaps 10 of the front wall are secured, preferably adhesively. This permits the body end walls and the body front wall being collapsed as illustrated in Fig. 4; also cover and end wall as there illustrated providing a box which is known as an infold box.

The joint flaps 13 have tongues 16 projecting from their front edges, these flaps being cut out of the bottom edges of the front wall corner flaps as is clearly shown in the blank of Fig. 5. When the container is erected, these tongues 16 project forwardly of the body front wall as is illustrated and retainingly engage the cover front wall when the cover is in closed position. The front wall corner flaps are preferably provided with lugs 17 which project from the bottom edges thereof and cut away from the end edges of the joint flap portions of the body end walls as is clearly shown in the blank of Fig. 5, these lugs 17 being adapted to firmly engage the bottom of the container when the container is erected to hold the body front wall in erected position and they also tend to hold the end walls in erected position to most effectively receive the cover.

To permit the collapsing of the container with these projecting lugs, the bottom is provided with slits 18 at the hinge of the front wall thereto, these slits receiving the lugs when the container is collapsed as is shown in Fig. 4. The container may be quickly set up to receive its contents and the cover closed and is effectively retained in closed position by the projecting tongues or lugs 16.

In the embodiment of my invention shown in Figs. 6 to 9, inclusive, the bottom 20 has a front body wall 21 and a rear body wall 22 hingedly secured thereto and also end body walls 23 hingedly connected to the ends thereof. The cover 24 is hingedly connected to the upper edge of the rear body wall. The cover is provided with a front wall 25 and end walls 26. The end body walls 23 are diagonally scored at 27 providing folding flaps and joint flaps 28 which have corner flap extensions 29 adhesively secured to the inner side of the front body wall 21. Tongues project from the corner flaps 29 substantially beyond the end of the front wall, these tongues being cut from the joint flap 28. The cover end walls 26 are provided with diagonal scores 31 which pro-

vide hinging flaps 32 which terminate in corner flaps 33 secured to the inner side of the cover front wall. This permits the collapsing of the end walls of the body and cover outwardly with the front body wall and the front cover wall collapsed inwardly in a manner known as an outward collapsed box.

The body end walls have inner rear wall or corner extensions 34 at their ends, these being slit at 35 to permit an overlapping, interlocking engagement as is illustrated in Fig. 7. The body end walls 23 have downwardly and forwardly inclined slits 36 extending from their rear ends and terminating in curved upward extensions 37 so that portions 38 thereof may be deflected inwardly to permit engagement of the rear ends of the cover end walls therewith as shown in Fig. 6. When the cover is closed it is retainingly engaged by the tongues 30 which may be deflected somewhat as shown in Fig. 9 in the event the cover end wall is of sufficiently close fit to necessitate such deflection. However, the cover is effectively retained substantially as in the embodiment shown in Figs. 1 to 5, inclusive.

I have not attempted to illustrate other embodiments or adaptations of my invention as it is believed that this disclosure will enable those skilled in the art to embody or adapt my invention as may be desired.

Having thus described my invention, what I claim as new and desire to secure by Letters Patent, is:

1. In a collapsible container, the combination of a body comprising a bottom and front and rear and end walls, the body front having corner flaps extending therefrom, a cover extending from the upper edge of the body rear wall and having cover and end front walls extending therefrom, the cover front wall having end flaps extending therefrom, the several parts being formed of an integral blank scored to provide hinged connections for the parts, the body end walls having diagonal scored or weakened lines at the front ends thereof of providing joint flaps collapsible on the outer sides of the body end walls and to which the corner flaps of the body front wall are secured permitting inward collapsing of the body end and front walls, the cover end walls having diagonal scores or weakened lines at their front ends providing joint flaps collapsible on the outer sides thereof and to which the corner flaps of the front cover wall are adhesively secured permitting inward collapsing of the cover end and front walls, the joint flaps of the body end walls having tongues projecting from the end edges thereof, said tongues being cut from the inner edges of the body front wall corner flaps and acting to retainingly engage the cover front wall when the cover is closed, the corner flaps of the body front wall having lugs projecting from the bottom edges thereof cut from the end edges of the body and wall joint flaps and acting to supportingly engage the bottom for supporting the front wall in vertical position when the container body is erected, the bottom having slits therein positioned at the hinge connection for the body bottom and front wall to receive said lugs when the container body is collapsed.

2. In a collapsible container, the combination of a body comprising a bottom and front and rear and end walls, the body front having corner flaps extending therefrom, a cover extending from the upper edge of the body rear wall and having cover end and front walls extending therefrom, the

cover front wall having end flaps extending therefrom, the several parts being formed of an integral blank scored to provide hinged connections for the parts, the body end walls having diagonal scores or weakened lines at the front ends thereof providing joint flaps collapsible on the outer sides of the body end walls and to which the corner flaps of the body front wall are secured permitting inward collapsing of the body end and front walls, the cover end walls having diagonal scores or weakened lines at their front ends providing joint flaps collapsible on the outer sides thereof and to which the corner flaps of the front cover wall are adhesively secured permitting inward collapsing of the cover end and front walls, the joint flaps of the body end walls having tongues projecting from the end edges thereof acting to retainingly engage the cover front wall when the cover is closed.

3. In a collapsible container, the combination of a body comprising a bottom and front and rear and end walls, the body front and rear walls having corner flaps extending therefrom, a cover extending from the upper edge of the body rear wall and having cover and end front walls extending therefrom, the cover front wall having end flaps extending therefrom, the several parts being formed of an integral blank scored to provide hinged connections for the parts, the body end walls having diagonal scores or weakened lines at the front ends thereof providing joint flaps collapsible on the outer sides of the body end walls and to which the corner flaps of the body front wall are secured permitting inward collapsing of the body end and front walls, the cover end walls having diagonal scores or weakened lines at their front ends providing joint flaps collapsible on the outer sides thereof and to which the corner flaps of the front cover wall are adhesively secured permitting inward collapsing of the cover end and front walls, the joint flaps of the body end walls having tongues projecting from the end edges thereof acting to retainingly engage the cover front wall when the cover is closed, the corner flaps of the body rear wall being foldable on the inner sides of the body end walls when the container is erected.

4. In a collapsible container, the combination of a body comprising hingedly connected bottom, front, rear and end walls, the body end walls having corner flaps extending from the ends thereof, a cover hingedly connected to the upper edge of the body rear wall and having cover front and end walls hingedly connected thereto, the cover end walls having corner flaps extending from the front ends, the body end walls having diagonal hinging lines at the front ends thereof providing folding flaps, the front corner flaps of the body end walls being secured to the inner side of the front wall, the folding flaps permitting outward collapsing of the body end walls and inward collapsing by the front wall, the rear corner flaps of the end walls being slotted to provide interlocking engagement when in erected position, the cover end walls having diagonal hinging lines at the front ends thereof providing folding flaps, the front corner flaps of the cover end walls being secured to the inner side of the cover front wall permitting outward collapsing of the cover end walls and inward collapsing of the cover front wall, the end of the body end walls having slots adjacent their rear ends to receive the rear ends of the cover end walls when the container is erected, the end wall corner flaps having tongues projecting from

the hinged edges thereof when the container is erected.

5. In a collapsible container, the combination of a body comprising hingedly connected bottom, front, rear and end walls, the body end walls having corner flaps extending from the front ends thereof, a cover hingedly connected to the upper edge of the body rear wall and having cover front and end walls hingedly connected thereto, the cover end walls having corner flaps extending from the front ends, the body end walls having diagonal hinging lines at the front ends thereof providing folding flaps, the front corner flaps of the body end walls being secured to the inner side of the front wall, the folding flaps permitting outward collapsing of the body end walls and inward collapsing by the front wall, the cover end walls having diagonal hinging lines at the front ends thereof providing folding flaps, the front corner flaps of the cover end walls being secured to the inner side of the cover front wall permitting outward collapsing of the cover end walls and inward collapsing of the cover front wall, the end wall corner flaps having tongues projecting from the hinged edges thereof when the container is erected.

6. In a collapsible container, the combination of a body comprising hingedly connected bottom, front, rear and end walls, the body end walls having corner flaps extending from the front ends thereof, a cover hingedly connected to the upper edge of the body rear wall and having cover front and end walls hingedly connected thereto, the cover end walls having corner flaps extending from the front ends, the body end walls having diagonal hinging lines at the front ends thereof providing folding flaps, the front corner flaps of the body end walls being secured to the inner side of the front wall, the folding flaps permitting outward collapsing of the body end walls and inward collapsing by the front wall, the cover end walls having diagonal hinging lines at the front ends thereof providing folding flaps, the front corner flaps of the cover end walls being secured to the inner side of the cover front wall permitting outward collapsing of the cover end walls and inward collapsing of the cover front wall, the end wall corner flaps having tongues projecting from the hinged edges thereof when the container is erected, said tongues being cut from the front ends of the end walls and acting to retainingly engage the cover end walls when the cover is closed.

7. In a collapsible container, the combination of a body comprising a bottom and front and rear and end walls, the body front wall having corner flaps extending from the ends thereof, a cover extending from the upper edge of the body rear wall and having cover front and end walls extending therefrom, the cover front wall having corner flaps extending therefrom, the said several parts being hingedly connected, the body and cover end walls having hinged joint flaps at their front end to which the corner flaps of the body front wall and cover front wall are respectively secured permitting the collapsing of the body and the cover, the body end walls having tongues disposed in the planes thereof and projecting integrally from their front edges when the container is erected which engage the front wall of the cover when the cover is closed to retain the cover in closed position, said tongues having a frictional sliding wedging-like engagement with the cover front wall when the cover is closed to releasably retain the cover in closed position.

8. In a collapsible container, the combination of a body comprising hingedly connected bottom, front and rear and end walls, the body front and end walls having foldable connections permitting the collapsing thereof, one of the foldably connected parts having tongues disposed in the planes thereof and projecting integrally outwardly therefrom when the container is erected, a cover hingedly connected to the upper edge of

10 the body rear wall and having cover front and end walls extending therefrom, the cover front and end walls being foldably connected to permit collapsing thereof, the cover end and front walls closing over the body front and end walls when the cover is closed with the cover end walls in retaining engagement with the said projecting tongues, said tongues having a frictional sliding wedging-like engagement with the cover end walls when the cover is closed to releasably retain the cover in closed position.

9. In a collapsible container, the combination of a body comprising hingedly connected bottom, front, rear and end walls, a cover hingedly connected to the upper edge of the body rear wall and having cover front and end walls hingedly connected thereto, the body front and end walls being foldably connected to permit the collapsing of the body of the container, the cover front and end walls having foldable connections permitting

25 the collapsing of the cover, the cover front and end walls being adapted to close over the body front and end walls, and the body having integral tongue-like projections at the front corners thereof over which the cover closes and acting 30 to apply expanding stress at the front corners of the cover when the cover is closed for retaining the cover in closed position.

10. In a container a body comprising a bottom,

and front and rear and end wall members, and a cover hingedly connected to the upper edge of the body rear wall member and having cover front and end walls, one of the body wall members having a tongue projecting integrally from

40 an end edge thereof adjacent the front of the body for a stressing retaining engagement with one of the cover wall members when the cover is closed, said body being formed of a blank and said tongue being formed by cutting the blank with a tongue on said body wall member and with a recess in a portion of the blank adjacent said body wall member, said tongue having a frictional sliding wedging-like engagement with said cover wall member when the cover is closed to releasably retain the cover in closed position.

KENNETH T. BUTTERY.
